UNITED STATES PATENT OFFICE.

GEORGE F. APPLEGATE, OF TRENTON, NEW JERSEY.

EYEGLASSES OR SPECTACLES.

SPECIFICATION forming part of Letters Patent No. 764,100, dated July 5, 1904.

Application filed October 19, 1903. Serial No. 177,711. (No model.)

To all whom it may concern:

Be it known that I, GEORGE F. APPLEGATE, of Trenton, in the State of New Jersey, have invented certain new and useful Improvements 5 in Eyeglasses or Spectacles, whereof the following is a specification, reference being had to the accompanying drawings.

My invention relates to a clamp of the frameless or rimless class arranged to maintain a 10 lens in proper relation with the nose bridge, guard, or other frame members and a lens of peculiar construction adapted to coöperate with said lens-clamp. A clamp of the class specified usually comprises straps to engage 15 the opposite sides of the lens, provided with registered circular openings to receive a screw entered through a corresponding aperture in the lens. It is characteristic of prior devices that said screw occupies a certain invariable 20 position in the lens-clamp, its location being determined by a circular seat or screw-threaded opening to which it is fitted in the clamp, and therefore the aperture in the lens must be accurately drilled at a certain distance 25 from the edge of the lens or else it must be enlarged to bring it into registry with the apertures in the clamp-straps before the clamp can be secured to the lens. It may be noted that the ordinary inaccuracies of manu- 30 facture are such that the latter expedient is frequently necessary.

It is an object of my invention to provide a lens-clamp which may be readily attached to a lens regardless of slight variations in the 35 location of the aperture in the lens, so as to avoid the aforesaid necessity for accurately drilling the lens or redrilling it.

To this end my invention comprises a lens-clamp which instead of being provided with 40 a circular aperture or seat fitted to receive and retain the screw-threaded member in invariable relation to the clamp is provided with an elongated slot or notch in which said member may be adjusted and engaged at different distances from the edge of the lens in correspondence with the location of the lens-aperture.

A further object of my invention is to provide a lens with a screw-threaded member

stationary therein and adapted to coöperate 50 with the peculiar form of clamp herein contemplated.

My invention comprehends the various novel features of construction and arrangement hereinafter more definitely specified. 55

In the drawings, Figure I is a perspective view of a fragment of a lens with a convenient embodiment of my invention applied thereto. Fig. II is a perspective view showing the opposite side of the parts shown in 60 Fig. I. Fig. III is a perspective view of the lens-clamp shown in Figs. I and II. Fig. IV is a perspective view of a modified form of lens-clamp. Fig. V is a perspective view of the bolt and nut shown in Figs. I and II. 65 Fig. VI is a side view of a modified form of clamp. Fig. VII is a perspective view of a fragment of a lens provided with an aperture to engage the clamp. Fig. VIII is a perspective view of a fragment of a lens provided 70 with a peripheral notch to engage the clamp. Fig. IX is a perspective view of a fragment of a lens with a modified form of my invention applied thereto. Fig. X is a perspective view showing the opposite side of the parts 75 shown in Fig. IX. Fig. XI is a face view of a lens provided with a stationary bolt. Fig. XII is a sectional view taken on the line XII-XII in Fig. XI. Fig. XIII is a sectional view of a lens, showing modified means for 80 securing the bolt in stationary position. Fig. XIV is a sectional view of the clamp shown in Figs. IX and X.

Referring to Figs. I, II, and III, the lens-clamp 1 comprises the flanged seat 2 to receive 85 the bridge and nose-guard members, and said seat is connected by the shank 3 with the plate, which comprises the wings 4, arranged to engage the edge of the lens 5, and the straps 6 and 7, which embrace the opposite faces of 90 said lens. As indicated in Figs. I, II, and III, said straps 6 and 7 are respectively bifurcated by slots or notches 8 9, which terminate adjacent to the wing members 4 and extend to the free ends of the straps. Said slots 8 9 are of 95 such extent as to register with the aperture 10 in the lens 5 regardless of such variations in the distance of said aperture from the edge of

the lens as are incident to rapid production of such lenses, and the clamp is secured to the lens by the screw-threaded bolt 13, whose head 14 encounters the outer face of the strap 6 and 5 whose nut 15 encounters the outer face of the strap 7. As shown in Fig. V, said bolt 13 is provided with a shoulder 16, having parallel sides adjacent to the head 14 for engagement with the parallel sides of the notch 8 in the strap 6 to prevent rotation of said bolt 13 when the nut 15 is rotated on the screw-thread 17 of said bolt.

In the form of my invention shown in Fig. IV the lens-clamp 19 comprises the single strap 20, provided with the notch 21, and the shank 22 is connected with said strap by the rib 23. In this form of my invention the shoulder 16 of the bolt 13 is of course engaged in the notch 21 in said strap 20, and the nut 15 contacts 20 with the face of the lens opposite to that in contact with said strap.

It may be noted that the clamp (shown in Figs. I, II, and III) above described is preferably made in two pieces—that is to say, the 25 seat 2 and shank 3 are in integral relation and primarily separate from the plate comprising the wings 4 and straps 6 7, said shank being united to said plate by a soldering operation. On the contrary, the form of clamp shown in 30 Fig. IV may be made integrally by successive stamping operations.

Referring to Fig. VI, the clamp 25 is provided with the strap 26, having its opposite edges serrated, as indicated at 27, to fit the 35 corresponding serrations in the bolt 28, so that the latter may be inserted in different positions with respect to the edge of the clamp and be prevented from accidental displacement therefrom.

40 Referring to Figs. IX, X, and XIV, the clamp 30 may be formed of a single sheet-metal stamping different from the clamp 19 (shown in Fig. IV) in that its shank 31 is at one side of instead of being centrally disposed 45 with respect to the thickness of the lens. The flange 32 of said clamp 30, which extends parallel with the edge of the lens, is reinforced at its junction with the strap 33 by the ribs 34, which may be conveniently stamped up 50 in integral relation with said strap and flange. As best shown in Figs. X and XIV, said clamp 30 is provided with a lug 35, fitted to the notch 36 in the lens 37, so as to prevent oscillation of the clamp upon the bolt 38, by which it is 55 secured to the lens, the head 39 of said bolt being in contact with one side of the lens and the nut 40 being in contact with the strap 33. As shown in Fig. XIV, said clamp 30, having the offset shank 31, permits the employment 60 of a bolt 42 and nut 43 to secure the nose-bridge 44 and guard 45 in proper relation to their seat 46. The head 47 of said bolt 42 being in contact with the inner face of said seat 46 an immediately-adjacent portion of said

bolt is squared or otherwise shaped to engage 65 a correspondingly-shaped aperture in said seat 46 to prevent rotation of the bolt.

The clamps above described being provided with straps having slots or notches extending to their ends it is unnecessary to employ therewith a bolt in detachable relation to the lens. Therefore in Figs. XI, XII, and XIII I have shown lenses provided with bolts in stationary relation to the lenses which are thus arranged to coöperate with the peculiar 75 clamps above described. The lens 49 (shown in Figs. XI and XII) is provided with the aperture 50, in which the bolt 51 is permanently secured by the bushing 52, which may be of cement, and said bolt is provided with 80 nuts 53 upon its opposite ends to engage the opposite faces of the clamp-straps. The lens 55 (shown in Fig. XIII) is provided with the bolt 56, which is fixed in the aperture 57 by means of the bushing 58, which latter may be 85 of metal or other material capable of being swaged to form shoulders 59 upon the opposite sides of the lens at right angles to the axis of said bolt 56, so that the straps engaged with said bolt come in contact with the opposed parallel surfaces of said shoulders 59 instead of in contact with the converging opposite faces of said lens 55, thus insuring a 90 more uniform distribution of the clamping-pressure on the strap.

95 Although I have shown in Figs. XI, XII, and XIII lenses provided with stationary screw-threaded members by which the clamps may be attached, it may be noted that the screw-threads may be omitted from said members and the clamps secured in the desired position of adjustment by upsetting the projecting ends of said members to form rivet-heads.

100 I do not desire to limit myself to the precise details of construction and arrangement herein set forth, as it is obvious that various modifications may be made therein without departing from the essential features of my invention.

110 I claim—

1. The combination with a lens, of a lens-clamp, provided with a screw-threaded member arranged to engage the lens and clamp, in invariable relation to the former, and in 115 variable relation to the latter, substantially as set forth.

2. The combination with a lens, of a lens-clamp, provided with a screw-bolt arranged to engage the lens and clamp, in invariable 120 relation to the former; and means arranged to engage said bolt at different distances from the edge of the lens, substantially as set forth.

3. The combination with a lens, of a lens-clamp having a member extending parallel to 125 the surface of the lens, arranged to register with an aperture in the lens; a screw-threaded member, arranged to engage the lens in

invariable relation, and adjustable in said clamp member in correspondence with variations in the location of said lens-aperture with respect to the edge of the lens, substantially as set forth.

4. The combination with a lens, of a lens-clamp having a strap comprising means to receive a screw-threaded member at different distances from the edge of the lens; a screw-

10 threaded member, in invariable relation with the lens, fitted in said strap, arranged to connect said strap and lens, and provided with means to prevent its rotation therein, substantially as set forth.

15 5. In a lens-clamp, the combination with a strap comprising an elongated slot; of a screw-bolt adjustable from end to end of said slot, arranged to connect said strap and lens, provided with means to prevent its rotation there- 20 in; and, a nut fitted to said bolt, substantially as set forth.

25 6. In a lens-clamp, the combination with a strap having an elongated slot with parallel edges; of a screw-bolt adjustable from end to end of said slot, arranged to connect said strap and lens, having a shoulder with parallel sides fitted to said slot to prevent its rotation therein; and, a nut fitted to said bolt, substantially as set forth.

30 7. In a lens-clamp, the combination with a shank provided at one extremity with a seat for the nose guard and bridge and at the other extremity with a strap comprising an elongated slot; of a screw-bolt comprising a shoulder arranged to engage said slot, adjustable from end to end thereof, in non-rotatable relation; and, a nut fitted to said bolt, substantially as set forth.

40 8. In a lens-clamp, the combination with opposed respectively bifurcated straps extending parallel with the opposite faces of the lens; of a screw-bolt provided with a shoulder arranged to engage one of said straps between its bifurcations, in non-rotatable relation; and, 45 a nut on said bolt, arranged to engage the other strap, substantially as set forth.

45 9. In a lens-clamp, the combination with a seat for the nose guard and bridge; of a shank extending from said seat; a strap extending 50 parallel with the lens in eccentric relation to said shank and comprising an elongated slot; and, means arranged to engage the lens through said slot, in adjustable relation to said clamp, substantially as set forth.

55 10. In a lens-clamp, the combination with a seat for the nose guard and bridge; of a shank extending from said seat; a plate, on said

shank, comprising wings to embrace the edge of the lens and a strap extending parallel with the face of the lens; said strap comprising an elongated slot; a screw-bolt adjustable from end to end of said slot, fitted in non-rotatable relation therein, in registry with an aperture in the lens; and, a nut on said bolt, substantially as set forth.

60 11. In a lens-clamp, the combination with a seat for the nose bridge and guard; of a shank extending from said seat; a strap extending from said shank, parallel with the surface of the lens, comprising an elongated slot; and, a 70 rib connecting said shank and said strap, substantially as set forth.

75 12. In a lens-clamp, the combination with a seat for the nose bridge and guard; of a shank; wings extending from said shank arranged to engage the edge of the lens; a strap extending from said shank parallel with the surface of the lens, comprising an elongated slot; and, a rib connecting said shank and said strap, substantially as set forth.

80 13. In an eyeglass or spectacle, the combination with a lens-clamp comprising a lug fitted to a notch in the edge of the lens; of a screw arranged to engage the lens and clamp in longitudinally-adjustable relation, substantially as set forth.

85 14. In an eyeglass or spectacle, the combination with a lens-clamp comprising a strap extending parallel to the surface of the lens, arranged to register with an aperture in the lens; of a screw entered through the lens, arranged to engage the lens and clamp, and adjustable in said clamp member toward and away from the edge of the lens, in correspondence with variations in the location of 90 said lens-aperture; and, a lug on said clamp fitted to a notch in the edge of the lens, substantially as set forth.

95 15. In an eyeglass or spectacle, the combination with a lens; of an attaching member entered through an aperture in said lens; means in said lens securing said member in stationary position; and, a lens-clamp arranged to engage said attaching member in different positions of adjustment with respect to the edge 100 of the lens, substantially as set forth.

In testimony whereof I have hereunto signed my name, at Philadelphia, Pennsylvania, this 16th day of October, 1903.

GEO. F. APPLEGATE.
